(57) **CLAIM**

The ornamental design for an semi-flush mounted air conditioner disconnect housing with moisture intrusion resistant flanges.

DESCRIPTION

FIG. 1 shows a front view of the semi-flush mounted air conditioner disconnect housing with moisture intrusion resistant flanges, and showing my new design;

FIG. 2 shows a rear view thereof;

FIG. 3 shows a left side view thereof;

FIG. 4 shows a right side view thereof;

FIG. 5 shows a top view thereof;

FIG. 6 shows a bottom view thereof;

FIG. 7 shows a front perspective view from the top left side thereof;

FIG. 8 shows a front perspective view from the top right side thereof;

FIG. 9 shows a front perspective view from the bottom left side thereof;

FIG. 10 shows a front perspective view from the bottom right side thereof;

FIG. 11 shows a rear perspective view from the top left side thereof;

FIG. 12 shows a rear perspective view from the top right side thereof;

FIG. 13 shows a rear perspective view from the bottom left side thereof;

FIG. 14 shows a rear perspective view from the bottom right side thereof;

FIG. 15 shows a left side view thereof, with the access cover in the open position;

FIG. 16 shows a front view thereof, with the access cover in the open position; and,

FIG. 17 shows a left side view thereof, with a dead front cover detached from the housing.
